UNITED STATES PATENT OFFICE.

JAMES H. TAYLOR, OF OWENSBORO, KENTUCKY.

DENTAL SURGICAL INSTRUMENT.

1,405,353.

Specification of Letters Patent. Patented Jan. 31, 1922.

Application filed October 25, 1920. Serial No. 419,206.

To all whom it may concern:

Be it known that I, JAMES H. TAYLOR, a citizen of the United States, residing at Owensboro, in the county of Daviess and State of Kentucky, have invented certain new and useful Improvements in Dental Surgical Instruments, of which the following is a specification.

This invention relates to dental surgical instruments and more particularly to an instrument designed for use in the operation of cutting away the bony process in which a maleducted molar has become impacted.

The object of the invention is to provide an instrument which may be conveniently manipulated without liability of injury to the patient and which will operate to smoothly cleave or cut away the portion of the bony process of the superior maxillary which has grown over the sides of the maleducted molar, and by the use of which instrument this portion of the bony process may by a single operation be cut away and removed leaving a smooth surface which will quickly heal.

In the accompanying drawings:

Figure 1 is a side elevation of one of the instruments embodying the invention, the view illustrating the manner in which the invention is to be employed in cutting away the bony process embedding the sides of the upper left third molar;

Figure 2 is a top plan view illustrating an instrument which is to be employed at the left hand side of the mouth.

Figure 3 is a top plan view of the instrument which is to be employed at the right hand side of the mouth;

Figure 4 is a front end elevation of the instrument, a portion of the blades being shown in section.

The instruments shown in Figures 2 and 3 of the drawings are structurally identical, the only difference being that one is adapted for use at the left hand side of the mouth, and the other at the right hand side of the mouth and therefore the specific description which is to follow will apply equally well to both instruments.

The instrument in either case comprises a pair of members one indicated by the numeral 1 and the other by the numeral 2, which members are disposed in crossed rela-

tion at their forward portions and connected by means of a pivot screw 3, the members 1 and 2 being provided with handle portions 4 and 5 respectively which may be knurled and suitably shaped to provide for most convenient manipulation of the instrument.

Forwardly beyond the pivot 3, the member 1 is extended laterally as indicated by the numeral 6, and thence upwardly and inwardly to provide a blade which is indicated in general by the numeral 7. The outer side of this blade is transversely and longitudinally curved and smooth throughout as indicated by the numeral 8 whereas the inwardly presented side of the blade is transversely and longitudinally concave as indicated by the numeral 9, the side and lower edge portions of the blade being sharpened to provide a cutting edge 10.

The member 2, forwardly beyond the pivot 3, is extended outwardly laterally as at 11, and thence upwardly and inwardly to provide a blade indicated by the numeral 12, this blade having the same form as the blade 7. By reference to Figures 1, 2 and 3 of the drawings it will be observed that the blades 7 and 12 have their concave faces presented toward each other.

By reference to Figure 1, which figure illustrates the manner of using one of the instruments, it will be observed that the molar A is maleducted and that as a result of the maleduct a portion of the maxillary C has grown over the sides of the molar, this being the upper left third molar. In order to permit of this impacted molar being lifted from its impression in the inferior maxillary, it is necessary that the portions of the bony process which embed the molar be cut away and this is accomplished by the use of the instrument shown in Figure 1, the instrument shown in Figure 2 being employed where a similar condition exists in the case of the upper right third molar. In the use of the instrument the same is so disposed that the concave faces of the blades 7 and 12 will be positioned at opposite sides of the molar A, and then by bringing pressure to bear against the handles 4 and 5, the blades 7 and 12 will be caused to cut through or cleave the bony process which embeds the respective sides of the said molar.

Rearwardly of the pivot 3, the members 1

and 2 are provided with shoulders 14 which coact to limit the pivotal movement of the members to bring the blades together.

Having thus described the invention, what is claimed as new is:

A dental surgical instrument comprising a pair of pivoted handle members provided forwardly of their pivot with extensions lat-

erally curved in opposite directions and then laterally curved inwardly toward each other, the oposing faces of the laterally inwardly curved portions of the extensions being formed with cutting edges presented toward each other.

In testimony whereof I affix my signature.

JAMES H. TAYLOR. [L.S.]
